[57] CLAIM

The ornamental design for a chair, as shown and described.

DESCRIPTION

FIG. 1 is a front perspective view of the chair thereof.

FIG. 2 is a rear perspective view thereof.

FIG. 3 is a top plan view thereof.

FIG. 4 is a right side elevational view thereof; and, FIG. 5 is a bottom plan view thereof.

The fragmented cross-hatching shown on the seat and backrest is understood to represent fabric and would be continuous throughout the implied areas.

FIGS. 3 through 5 have been shown on a smaller scale with respect to FIGS. 1 and 2.
